ATTACHMENT FOR CROCHETING
MACHINES

Morris Philip, New York, N. Y.

Application October 10, 1947, Serial No. 779,051

7 Claims. (Cl. 112—116)

1

This invention relates to the art of machine-crocheting, and, in particular, to attachments for crocheting machines of the type exemplified by the disclosure in U. S. Patent No. 1,125,437, issued January 19, 1915, to Avis.

An object of the invention is to provide a novel and simple attachment for such a machine whereby the needle may be prevented from reciprocating while other parts of the machine are operating their respective normal manners for the purpose of causing the machine to form chain stitches without also alternately forming regular stitches through, for instance, the selvage of a piece of fabric to which the crochet work is to be applied. Where, for example, the machine is used for crocheting an ornamental border or binding on the selvage of a piece of fabric, my attachment operates to cause the machine to produce chained crochet work that is but intermittently anchored to the selvage and at intervals greater than those corresponding to the normal periodicity of reciprocation of the needle.

A further object is to provide a novel thread holder.

Generally, the invention seeks to provide a novel and simple means whereby crocheting machines of the type mentioned may be caused to operate to form linked chain stitches independently of stitches anchoring the crochet work to the fabric, or chain stitches each anchored to the fabric, or any of a variety of combinations of anchored and unanchored chain stitches, as desired. With the attachment of my invention such a machine may be used to execute a crocheted border upon the selvage, for instance, of a piece of knitted fabric, such as that forming a sweater, the border comprising a series of chain stitches each linked to the selvage, in the usual manner, said series being interrupted at predetermined intervals by a hiatus of links or stitches engaging the fabric selvage, for the purpose of producing button holes or other openings between the crochet work and the selvage.

In the drawings:

Fig. 1 is an elevational view of a crocheting machine of the type mentioned, having thereon one modification of the attachment of the present invention. The operator normally sees the machine from the angle of view of the figure, and, for convenience, this side is referred to as the operator's side. The upper portion of the well-known needle-bar is omitted to condense the drawing.

Fig. 2 is an elevational view of the lower part

2

of the machine seen at 90° to the operator's side, and to the operator's left. A covering (of the common feed-mechanism housing) is removed in this figure to expose certain internal parts. Certain upper parts of the machine are omitted in this figure as they are immaterial to the illustrative purposes of the figure.

Fig. 3 is an elevational view of the machine from the operator's side, showing parts of the machine cut away and in section and certain normally obscured internal parts.

Fig. 4 is an enlarged detail of the cast-off horn mechanism positioned outside the machine housing; the same is less clearly seen in Fig. 2.

Fig. 5 is the section 5—5 of Fig. 4.

Fig. 6 is a schematic rectilinear perspective view, with certain parts omitted, showing one modification of my attachment and certain usual parts of such a crocheting machine that specially cooperate with my attachment. Much of the usual crocheting machine is not shown in the drawing for the purpose of clarity in illustrating the relationship between the actual crocheting elements of the machine and my attachment.

Fig. 7 is an interior elevational view of the common crochet-hook carrier, showing, also, beyond the carrier, its guide plate.

Fig. 8 is a partly sectional elevational detail of the means provided in my attachment for engaging and disengaging the needle-bar clamp of the usual machine of this type.

Fig. 8A is a schematic illustration, greatly enlarged and purposefully exaggerated, of a short section of thread pattern possible to be duplicated upon the usual crocheting machine when fitted with my attachment. The pattern illustrated is merely exemplary: the anchored and unanchored chain stitches may be distributed in a variety of combinations other than that illustrated.

Figs. 9 to 26, inclusive, illustrate in perspective, and somewhat schematically, various stages of operation of the actual crocheting elements of the machine when controlled by the attachment of my invention. The figures are more particularly described in the text, below. In these figures the illustrations are limited to the needle, the thread holder, the crochet-hook, the cast-off horn, the chaining finger and the thread, and all operative parts are shown partly erased. The

fabric the edge of which is to be crocheted is not shown because illustration of the fabric would have obscured the figures; the line of penetrations of the fabric selvage by the needle will of course be understood to be approximately along

the edge of the chaining finger that is to the left in the figures.

Figs. 27, 28, 29, and 30 illustrate a modification of my attachment.

Fig. 27 is a fragmentary elevational view of a crocheting machine of the type mentioned, seen from the operator's side, and showing only part of the machine to the operator's right, and the modification of the attachment.

Fig. 28 is the section 28-28 of Fig. 27, and principally illustrates a cam and its driving arrangement.

Fig. 29 is a view, from the angle of view of Fig. 28, of a disk, or base plate, upon which elements are mounted to form such a cam as is seen in Fig. 28.

Fig. 30 is a perspective view of an element employed in building up such a cam.

As the present invention relates to an attachment, and modifications thereof, for a crocheting machine of the type exemplified by the disclosure in the cited patent, and so that a full understanding of the function and utility of the attachment may be had, I have shown, in Fig. 1, an elevational view of such a crocheting machine with one modification of my attachment applied thereto. Fig. 1 shows the crocheting machine as it would normally be seen by the operator.

The patent cited employs certain terminology that has become common among those skilled in the related art, and for this reason I follow herein substantially the usage of Avis in referring to parts of the machine.

In Fig. 1 the needle is designated as 11; the needle clamp 12; the needle bar 13; and the needle-bar clamp 14. In an unmodified machine of the type shown the needle-bar clamp is linked to a lever 15, pivoted to the body of the machine at 16, and engaged at one end by a pitman 17 connecting with an eccentric 18 mounted on a drive shaft 19 adjacent to a pulley 20 by means of which power may be applied to the machine, and normally cause the needle bar to reciprocate vertically as a function of the revolution of the drive shaft.

However, in applying to such a machine the modification of my attachment partly illustrated in Figs. 1 and 2, and more fully illustrated in Fig. 6, I remove the usual link between the needle-bar clamp and the lever; and substitute for such link a special latch 23 (see, also, Fig. 8), which is more particularly described below. The usual link is not shown in the drawings; however, the loci of pivotal attachment of such link to the needle-bar clamp and lever, respectively, are of importance in the structure and application of my attachment, and these loci have been designated 21 (where the link is customarily attached to the needle-bar clamp) and 22 (where the link is customarily attached to the lever).

Fig. 3, an elevation from the angle of view of Fig. 1, shows the machine partly broken away and partly in section to illustrate certain internal parts.

Mounted on the drive shaft 19 and upon a shaft 24, respectively, are two cams, 25 and 26, geared together, and controlling the operation of a carrier 27 of the crocket-hook 28 in the usual manner. To the left of cam 25, in Fig. 3, the drive shaft 19 is seen to pass through a partition wall 29 and into the housing of the well-known mechanism for controlling the feed of fabric applied to the machine for crocheting. In Fig. 2 part of this mechanism is exposed, as by removal of the cover of the housing. In Fig. 2 drive shaft 19 is shown

to be provided on its near end with a driving gear 30 which is in mesh with a larger gear 31, the latter directly governing the feed mechanism.

The usual presser foot is designated 32, and the needle plate 33 (cf. Figs. 1, 2, and 3); the chaining finger is designated 34 (cf. Fig. 6). In applying my attachment to a machine of this type, I remove the usual supplemental thread holder and substitute therefor, and within the same mounting means, a specially formed thread holder 35, which is more particularly described below.

The usual cast-off horn is designated 36. Fig. 6 fully illustrates the well-known mechanism whereby the rotary motion of the drive shaft 19 is translated through shaft 24 to effect oscillatory movement of the cast-off horn 36 and the thread holder 35 (see, also, Fig. 4).

To this point I have described briefly the common elements of crocheting machines of the type mentioned above and illustrated in the drawings; particularly I have described the salient elements to be found in a crocheting machine such as described in the Avis patent, supra. I have mentioned two replacement elements: (1) my latch 23, which, in one modification of my attachment, takes the place of the usual link (e. g. link 5 of Avis) connecting the needle-bar clamp and the (needle-bar) lever (15 in the present drawings); and (2) my specially formed thread holder 35, which is substituted for the usual supplemental thread holder (30 of Avis).

I now describe the structure and function of one modification of my attachment. However, as a preamble to a description of a specific structure, I point out, immediately following, certain normal operations of a crocheting machine of the type mentioned which, by means of my attachment, it is intended to vary.

In a crocheting machine such as that of Avis the needle bar moves downward and upward during each revolution of the drive shaft; and, of course, if fabric is being fed through the machine, and the needle is supplied with thread, the needle penetrates the fabric one time for each revolution of the shaft and so effects one anchored stitch in connection with what is referred to as a chain stitch. Thus, without respect to the rate of feed of the fabric, each crocheted pattern made along the edge or selvage of the fabric during a single revolution of the drive shaft is necessarily linked to the fabric. Obviously a great variety of patterns may be had with the unmodified Avis machine, the differences being functions of the rate of feed; for example, if the feed is such that the fabric does not move forward for each revolution of the shaft, but only after a number of revolutions, a like number of penetrations by the needle will take place and a so-called bunched pattern will result. But, on the unmodified machine, it is not possible to make a chain without also anchoring the chain to the fabric if the latter is present in the machine.

The attachment of my invention has the especial purpose of providing means whereby each crocheted pattern made per revolution of the drive shaft need not be linked or anchored to the edge or selvage of the fabric; and to accomplish this result my attachment has as one of its principal functions the prevention of downward movement of the needle bar (and, of course, the needle itself) during certain selected and predetermined revolutions of the drive shaft when other elements are operating in their respective

normal manners, so that a strand of thread is not carried through the edge or selvage of the fabric during any such revolutions.

The operation of a machine of the type of Avis is well known, but a brief restatement of certain elementary functions will be of aid in understanding the reasons for functions of my attachment. In the Avis machine, for example, if it be assumed that the needle, supplied with thread, has penetrated the edge of the fabric, the advanced crochet-hook, being then beneath the chaining finger and fabric, and being then retracted, catches a lead of the needle thread and draws the lead, in the form of a loop laterally beneath the chaining finger; then, as the needle is withdrawn from the fabric upwardly, and the crochet-hook retracted beyond the chaining finger and oscillated upwardly, the crochet-hook is again advanced over both the chaining finger and the fabric, carrying the loop of needle thread around the chaining finger, and the crochet-hook, on being retracted from this second advance, catches another lead of the needle thread between the uplifted needle and the fabric and draws this second lead, also in the form of a loop, laterally above the chaining finger; and this basic operation is continuously repeated, the first loop subsequently slipping through the second loop, and so on, forming what are known as chains.

This operation makes a thread pattern having a lead of the thread passing twice through one hole in the fabric, the other ends of the lead being knotted against the outer edge of the fabric; and, in terms customarily employed in the art, a regular chain stitch is the result. Obviously the entire unit pattern is linked to the fabric. The thread leads pass beneath and above the chaining finger and are knotted on the edge of the finger away from the edge of the fabric.

It will be obvious that if the needle is prevented from descending through the fabric during a revolution of the drive shaft immediately following a series of normal operations of the machine, the crochet-hook will have completed a last stitch in the normal manner, but that upon the advance of the crochet-hook next beneath the chaining finger and the fabric no new lead of thread will be present for the crochet-hook to catch; and after the crochet-hook is retracted, turned upwardly, and again advanced in the usual manner, this time over the chaining finger and fabric, the needle thread (i. e., that strand leading directly to the eye of the needle from the pattern upon the crochet-hook itself) will be out of position to be caught by the crochet-hook on its immediately following retraction. Plainly the thread lead will not be a normally taut vertical lead, but will simply be a loosely swinging strand assuming various amorphous positions due to the continued movements of the crochet-hook and the static condition of the needle eye. Thus, if the needle-bar (and needle) remained statically withdrawn from the fabric and the other elements of the machine continued to operate in their respective normal manners the feed would eventually effect the drawing off of all thread from the crochet-hook and the chaining finger and the carrying off of the thread along with the advancing fabric, only a single unknotted and unlooped strand of needle thread connecting the last-formed thread pattern of crochet work with the needle eye and the usual storage spool.

But if means are provided whereby during the revolution or revolutions when the needle is in-

operative the lead from the needle's eye is always maintained in proper position and taut so that the crochet-hook upon retraction following its advances above the chaining finger and the fabric can catch the lead, it may be demonstrated that a series of chain stitches may be made none of which, except, of course, the first, and, if desired, the last, need be anchored to the fabric, but which will form on the edge of the chaining finger away from the edge of the fabric.

In one modification of my attachment I provide, as part of the means for selectively preventing operation of the needle-bar during one or more revolutions of the drive shaft 19, a latch 23 15 as a substitute for the link normally employed in machines of the Avis type to connect the needle-bar clamp with the needle-bar lever. The latch 23 (see Figs. 1, 3, 6, and 8) is substantially a bellcrank having a dog 37 formed at the heel thereof. One arm of the bellcrank is pivotally mounted upon the end of the lever 15 at 22, one of the loci of pivotal connection of the discarded link abovementioned. When the lever 15 is positioned as shown in Figs. 1, 3, and 6, the dog 37 20 engages a pin equivalent to the link pin originally provided at 21 within a channel in the needlebar clamp.

To the other end of the bellcrank is attached a rod 38 which connects the bellcrank with the 30 outer end of a radial arm 39 which is fixed by a set screw 40 on a shaft 41 journaled in a bore 42 of the partition wall 29 and in another bore 43 of an upright member 44 fixed to the base of the housing of the feed mechanism of the machine. 35 This connection, which is pivotal at each end, is best illustrated in Fig. 6.

In Fig. 1 all parts of the connection outside the housing of the feed mechanism may be seen; in Fig. 2 at the end of the shaft 41 and the up- 40 right member 44 may be seen. Those parts of the connection not shown in Fig. 1 are seen from the same angle of view in Fig. 3.

On the end of the shaft 41, beyond the up- 45 right member 44, is fixed a radial pin 45 (cf. Fig. 6). Upon the outer face of the gear 31 of the feed mechanism (usually eight to one in ratio to the driving gear 30) I affix a disk 46 concentric with gear 31. This disk 46 is provided, arbitrarily, with eight holes, preferably threaded, 50 and angularly spaced and at equal radial distance from the center of the disk. Two of such holes are designated as 47, 47.

Into these holes, 47, 47, or any of them, I 55 insert pins 48, preferably threaded, in such arrangement as desired. As the gear 30 is upon the drive shaft 19 its revolutions are synchronous with the revolutions of the latter; assuming the ratio of gear 31 to gear 30 to be, as is often the case in the art, eight to one, gear 31 will revolve 60 once for each eight revolutions of shaft 19, or, for each revolution thereof, one of the eight holes 47 will be brought into a given position with respect to the radial pin 45; and, if a pin 48 is present in a hole 47 so brought into position, the pin 65 48 will engage the pin 45, and effect a slight rotary movement in shaft 41 which operates to revolve the radial arm 39 slightly and to depress by means of the rod 38 the latch on the center 22, thereby withdrawing the dog 37 from the pin at 21, and effectively disengaging the lever 15 from the needle-bar clamp 14.

The arrow in Fig. 2 and that in Fig. 6 indicate the direction of rotation of the gear 31 and disk 70 46. Obviously the contact of the pins 48 and

45 tends to rotate the shaft 41 counterclockwise. This action, against a retractile helical spring 49, arranged normally to preserve the relationship of parts seen in Figs. 1, 2, and 6, operates to prevent the needle-bar from descending during any revolution of the drive shaft 19, corresponding to the presence at pin 45 of any hole 47 having a pin 48 therein.

It will be obvious that if suitable means for preventing the needle-bar from dropping merely by gravity, such as a spring (not shown), is provided, the bar cannot operate during a revolution of the drive shaft that effects release of latch 23, yet during such revolution other parts whose movements are functions of such revolution will operate in their usual manners. While the spring 49 serves to effect reengagement between the dog 37 and the pin at 21 after the lapse of contact between a pin 48 and pin 45, if the next revolution of the drive shaft brings another pin 48 into contact with pin 45 the needle-bar is again prevented from descending. It will be obvious that by arranging the pins 48 in the holes 47 of the disk 46 a considerable variety of patterns of operations of parts may be had.

The supplemental thread holder 20 of Ayis, for example, is oscillated back and forth across the path of the needle by well-known means. I substitute for his supplemental thread holder a specially designed thread holder 35 having at the lower end an eye, one wall of which is interrupted at the side of the thread holder, as seen in Figs. 9 et seq., so that the eye comprises substantially two oppositely positioned hooks. The function will be readily understood from the following: When the needle thread is drawn upward by the needle after a penetration by the needle of the fabric, a loop of the thread will have been caught beneath the fabric by the crochet-hook, and will be in process of being carried around the chaining finger; the lead of thread directly connecting the eye of the needle with the hole pierced in the fabric will necessarily be more or less taut, and held in position to be caught above the fabric by the crochet-hook when the latter begins its retraction after its advance over the chaining finger and fabric. But once such a complete cycle of operation has taken place—i. e., after the crochet-hook has once caught a loop of thread above the fabric—if the needle-bar is prevented from descending during the next revolution of the drive shaft, on neither the retraction of the crochet-hook after its advance beneath the chaining finger and fabric nor its reaction after its advance above the chaining finger and the fabric will the crochet-hook catch a new lead of thread, for no such new lead will be present in a proper position. The thread holder 35 that I substitute for the usual thread holder, as it swings toward the operator over the path of the needle, catches the strand of thread directly connecting the eye of the needle with the last hole pierced in the fabric, and retains this strand within the interrupted eye of the thread holder 35 until a subsequent descent of the needle-bar takes place. Thus, after the crochet-hook catches the thread as it retracts after a last normal advance above the chaining finger and fabric, and proceeds through that part of its cyclic movement beneath the chaining finger and fabric, and returns again above the finger and fabric, the thread is still held in proper position by the thread holder, notwithstanding the fact that the needle-bar has not again reciprocated.

Thus, so long as the needle-bar is prevented from descending, the lead of thread from the eye of the needle remains within the eye of the thread holder 35, and upon each retraction of the crochet-hook after a cyclic advance above the chaining finger and fabric a loop of thread may be caught, so that a series of chains may be made none of which, excepting the terminal stitches, are connected to the selvage of the fabric, but, instead, form on the edge of the chaining finger away from such selvage.

Upon the next descent of the needle, however, the thread is withdrawn from the eye of the thread holder 35 and does not reenter such eye until the needle is withdrawn again from the fabric.

I show, in Figs. 9 to 26, inclusive, greatly enlarged details illustrative of various stages of the operation of the crocheting machine with my attachment applied thereto.

In Fig. 9, parts of the needle, the thread holder, the crochet-hook, the cast-off horn, chaining finger, and thread are seen. In this figure, the needle is assumed to have just completed a penetration of and withdrawal from the fabric; obviously, then, the crochet-hook will have completed one cycle of movement beneath the chaining finger, have caught the needle thread as the needle was being withdrawn from the fabric, and have begun a retraction in its cyclic movement above the chaining finger. See the arrow which in Fig. 9 indicates the direction of movement of the crochet-hook 28. Notice that a loop of thread without a knot is shown upon the crochet-hook. In Fig. 9 the retracting crochet-hook is about to engage the thread above the chaining finger; notice also that the thread, between the chaining finger (i. e., the fabric) and the eye of the needle has entered the eye of the thread holder 35. The thread holder has begun to move away from the operator as indicated by the arrow in Fig. 9. This figure particularly illustrates the function of the thread holder 35. As it oscillates back and forth, although the needle itself might not move, the thread is repeatedly brought into position to be engaged above the chaining finger and fabric by the crochet-hook on its return movement after an advance over the finger..

In Fig. 10, a continuation of the operation is shown. The cast-off horn 36 is being retracted by the mechanism (not shown here) which operates to oscillate it and the thread holder at a predetermined periodicity, such mechanism, of course, being part of the usual machines of the type described. The crochet-hook has pulled the needle thread into the forward side of the eye of the holder 35; the latch of the crochet-hook has been closed; and the loops of thread upon the crochet-hook are being withdrawn therefrom.

Fig. 10A shows a detail of the knot seen on much smaller scale in Fig. 10.

In Fig. 11 the operation is shown to have progressed further. The crochet-hook has been retracted to its extreme position, and is on the point of moving forward again from another cycle, this time beneath the chaining finger. The horn 36 has been retracted from the work. The two loops shown on the crochet-hook in Fig. 9, and also seen slipping therefrom in Fig. 10, are shown here, in Fig. 11, to have been withdrawn altogether from the crochet-hook, and to be supported by the leads of that loop of needle thread caught by the crochet-hook in Fig. 10.

Fig. 12 illustrates an immediately following stage in the operation. The crochet-hook has moved forward again, this time beneath the chaining finger. Only one loop of thread remains upon the crochet-hook, which has engaged no further portion of the thread in moving, in this cycle, beneath the chaining finger for the reason that the needle has not again penetrated the fabric.

Fig. 13 is an enlarged detail of the conditions obtaining in Fig. 12.

In Fig. 14 the process is continued. The crochet-hook, shown near its extreme forward position in Figs. 12 and 13, has been retracted and still holds the loop of thread which it carried through its last cycle. Here, in Fig. 14, the cast-off horn is moving toward the work.

In Fig. 15, showing the succeeding stage of operation, the crochet-hook is being raised preparatory for its next cycle of movement over the chaining finger; and the cast-off horn has passed over the work.

In Fig. 16 the crochet-hook has moved forward over the cast-off horn and over the chaining finger, the horn having forced the single loop shown upon the crochet-hook in Figs. 11, 12, 13, 14, and 15, and also in the present figure (Fig. 16) posteriorly with respect to the latch of the crochet-hook.

In Fig. 17 conditions immediately succeeding those illustrated in Fig. 16 are depicted. The forward-moving crochet-hook has passed over the chaining finger and has substantially reached the limit of its forward movement; the cast-off horn has forced the single loop upon the crochet-hook back beyond the latch thereof.

In Fig. 18, showing a stage following that illustrated in Fig. 17, the crochet-hook is being again retracted. The loop thereupon, and behind the latch, is being drawn off the crochet-hook, and is swinging the latch to closed position. The cast-off horn has held the loop on the crochet-hook during the forward movement thereof (cf. Fig. 17), and still engages the leads of the loop even as the latter tends to close the latch and slip off the crochet-hook as the latter retracts. But this causes the crochet-hook to catch one lead of the same loop (i. e., that lead connecting directly with the eye of the needle), and so to form another loop.

In Fig. 19 I show the continuation of retraction of the crochet-hook: the cast-off horn still holds the work, forcing the most posterior loop off the crochet-hook, over the latch; and, as may clearly be seen, will presently force the loop over the loop held within the actual hook of the crochet-hook, and so force the first loop mentioned, immediately above, off the crochet-hook altogether. The new loop, i. e., that caught, in Fig. 19, within the actual hook of the crochet-hook and separated from the withdrawing loop by the latch, which is closed, will be drawn through the withdrawing loop to form another chain link.

In Fig. 20 I illustrate a succeeding stage wherein the needle is again operated, and is shown moving downward to penetrate the fabric. The cast-off horn has been withdrawn and is no longer in contact with the work. The crochet-hook is substantially at the end of its retractive movement, and is dipping again to begin a cycle of movement beneath the chaining finger.

Fig. 21 shows the needle nearing the end of its downward movement; the crochet-hook is passing beneath the chaining finger. Fig. 22 shows an immediately succeeding stage. The needle is nearly at the end of its downward movement, and the crochet-hook is beginning to be retracted. In

Fig. 23 the hook (dotted lines) of the crochet-hook is seen catching the thread near the eye of the needle. Of course it will be understood that the eye of the needle, in Fig. 23, is beneath the fabric to which crocheting is being applied.

In Fig. 24 the crochet-hook has been fully retracted and is being turned upward for its next cycle of movement over the chaining finger. It will be seen that the crochet-hook now has two loops upon it, the new loop of Fig. 19 and the new loop of Fig. 23. In Fig. 25 both the crochet-hook and the cast-off horn are advancing in their respective paths. The crochet-hook is now moving over the chaining finger; the cast-off horn has passed over and is engaging the work and preventing it from slipping off the crochet-hook.

The process is continued in Fig. 26, in which figure it will be seen that conditions illustrated in Fig. 9 are immediately to obtain.

Figs. 9 to 26, inclusive, illustrate the steps and stages in the operation of the machine with my attachment applied thereto to produce the following pattern: Beginning with a single regular stitch, comprising two leads of thread of a single loop, the loop being upon the crochet-hook and both leads passing through the same hole in the fabric, the crochet-hook catches the lead of the same loop above the fabric and between said hole and the eye of the needle; then, while the needle is stationary, the crochet-hook draws the last-named lead, as a loop, through the other two loops upon itself; the last-named two loops are forced off the crochet-hook by means of the cast-off horn as a chain link not directly connected with the fabric. Until the needle is again operated the machine will continue, if driven, to produce a series of such chain links not connected to the fabric but upon the edge of the chaining finger away from the fabric.

It will be clear from the foregoing that a machine of the Avis type, with my attachment thereon, may operate in a normal manner, i. e., specifically, may operate so that the needle pierces the fabric at every revolution of the drive shaft, or may operate so that the needle does not pierce the fabric at certain revolutionary periods and thereby make a series of chains spaced from the edge of the fabric by the chaining finger and not containing leads directly linked to the fabric. Thus by predetermining by any suitable means the periodicity of reciprocation of the needle-bar with respect to the periodicity of cyclic movements of the crochet-hook any combination of stitched chains and unstitched chains may be made.

Figs. 27, 28, 29, and 30 illustrate a modification of my attachment.

In this modification I do not utilize the larger gear 31 of the feed mechanism of the crocheting machine, but, instead, I remove the pitman 17 and eccentric 18 altogether; and in place of the eccentric I fix to the drive shaft 19 a gear 60, which, as shown in Fig. 27, engages a gear 61 journaled on a stub shaft 62 preferably drive-fitted into a bracket 63 fixed to the body of the machine by screws at 64 and 65.

The gear 61 is retained on the stub shaft 62 by any suitable means, such as a collar 66. That end of the lever 15 normally engaged by the removed pitman 17 is fitted with a pin 67 on which a sleeve 68 is rotatably mounted and secured. The sleeve 68 is received within a continuous channel 69 formed by a series of elements forming a cam structure 70 which is fixed to the face of the gear

61 opposite the body of the machine, as shown in Fig. 27.

As the gear 61 is rotated in mesh with the gear 60 the lever 15 is caused to oscillate according to the configuration of the channel 69, which, it will be presently shown, may be varied as desired.

Fig. 28 is the section 28—28 of Fig. 27. An exemplary arrangement of the cam structure 70 is shown, which provides for one descent of the needle-bar upon each fourth revolution of the drive shaft 19.

The cam structure may be varied easily on account of the simplicity of its elements. For example, the gear 61 may be provided with a boss 71 of only slightly less diameter than the gear itself; and this boss, which may, if desired, be a separate element, such as a disk fitted to the gear 61 concentrically by suitable means, is shown in Fig. 29 to be provided with a number of spaced tapped holes 72 arranged to receive screws 13 by means of which various elements 74 (one of which is shown in rectilinear perspective in Fig. 30) may be attached to the boss 71 for the purpose of assembling variably a cam to control lever 15. Fig. 30, showing one such element, also shows the screw holes 75, 75, therein to be countersunk so that flathead screws may be used as a convenience in the relatively limited space available.

The elements 74 are of two kinds: one, such as that shown to the bottom left in Fig. 29 and in Fig. 30, having a channel therein which is concentric with the gear 61 so that when the sleeve 68 is traveling in such channel no oscillatory movement will be translated to the lever 15; and another, such as that shown to the upper right in Fig. 29, having a channel therein which is terminally concentric with the gear 61 but which is centrally provided with a cusp so that when the sleeve 68 is traveling in such channel the lever 15 will oscillate through one down and up cycle. It will be understood that while I have described but two forms in which my attachment may be reduced to practice in connection with a crocheting machine of the type mentioned, these two forms are equivalent and that other equivalents are contemplated; and that a variety of equivalents of the two described means for controlling reciprocation of the needle-bar in association with revolutions of the drive shaft will now be apparent to those skilled in the art.

I claim:

1. In a crocheting machine of the class described, a needle supplied with thread; a needle bar; a crochet hook; a supplemental thread holder; a drive shaft; a cam driven by said drive shaft at a rate less than that of said shaft, said cam being shaped to effect reciprocation of said needle-bar in response to certain ordinal revolutions of said drive shaft and not in response to other ordinal revolutions thereof; another cam driven by said drive shaft and shaped to operate said supplemental thread holder in response to every revolution of said drive shaft; a third cam driven by said drive shaft and shaped to operate said crochet hook in response to every revolution of said drive shaft; and said supplemental thread holder having an eye with one wall thereof slotted so that after each reciprocation of said needle bar the needle thread is received in said eye through the slotted wall thereof and held in the path of said crochet hook until the next reciprocation of said needle bar.

2. In a crocheting machine of the class described, having a needle bar, a needle-bar lever, and a drive shaft, means for effecting oscillation

of said lever and reciprocation of said needle bar during certain predetermined revolutions of said drive shaft and for preventing oscillation of said lever and reciprocation of said needle bar during other revolutions of said drive shaft, said means comprising a cam driven by said drive shaft, said cam being a disk having a circuitous channel in one face thereof, an end of said lever being received in said channel, and a gear on said disk coaxial therewith and engaging another gear mounted on said drive shaft, the ratio of the gears being such that a plurality of revolutions of said drive shaft is required to effect one revolution of said cam, and a thread holder with an eye having one wall slotted so that after each oscillation of said lever and reciprocation of said needle bar the needle thread is received in said eye through the slotted wall thereof and held taut until the next reciprocation of the needle bar.

3. The means of claim 2 wherein said cam is a disk made up of a plurality of elements of common angular extent, each of said elements being secured to said gear coaxial with said disk, each of said elements being provided with a channel the ends of which are in register with the adjacent ends of the channels of contiguous elements, and some of said elements having channels concentric with said disk and other of said elements having channels shaped to effect oscillation of said lever as the same is engaged by such others of said elements.

4. In a crocheting machine of the class described, having a needle supplied with thread, a needle bar, a needle-bar lever, a supplemental thread holder, a crochet hook, and a drive shaft, means for effecting reciprocation of said needle in response to certain ordinal revolutions of said needle in response to certain ordinal revolutions of said drive shaft and not in response to other ordinal revolutions thereof, said means comprising a latch normally connecting said needle-bar lever with said needle bar, a cam driven by said drive shaft, a link attached to said latch and engaged by said cam periodically during predetermined revolutions of said drive shaft thereby effecting unlocking of said latch and enabling said needle-bar lever to move independently with respect to said needle bar.

5. The means of claim 4 wherein said cam is a gear driven by said drive shaft having a number of angularly spaced and removable pins mounted on the face of said gear, and a bell crank one arm of which is periodically engaged by each of said pins and the other arm of which is connected to said link, so that when a pin mounted on said gear engages an arm of said bell crank said link operates to withdraw the latch from said needle bar and prevent its movement with that of said needle bar lever.

6. In a crocheting machine of the class described, a needle supplied with thread; a crochet hook; a thread holder having an eye with one wall thereof slotted; a drive shaft; and cams driven by said drive shaft, a first cam thereof effecting reciprocation of said needle in response to certain ordinal revolutions of said drive shaft and not in response to other ordinal revolutions thereof, and a second cam thereof effecting reciprocation of said crochet hook and of said thread holder in response to each revolution of said drive shaft.

7. In a crocheting machine of the class described, a needle supplied with thread; a crochet hook; a thread holder having an eye with one wall thereof slotted; a drive shaft; and cams

driven by said drive shaft, a first cam thereof effecting reciprocation of said needle in response to certain ordinal revolutions of said drive shaft and not in response to other ordinal revolutions of said drive shaft, and a second cam thereof oscillating said crochet hook and said thread holder together across the path of said needle in response to each revolution of said drive shaft.

10 MORRIS PHILIP.
